CLAIM

The ornamental design for a swinging waste receptacle lid, as shown and described.

DESCRIPTION

FIG. 1 is a front perspective view of a swinging waste receptacle lid showing our new design;

FIG. 2 is a rear elevation view thereof.

FIG. 3 is a front elevation view thereof.

FIG. 4 is a side elevation view thereof, the opposite side elevation view being a mirror image of that shown;

FIG. 5 is a front perspective view thereof, showing the lid door in open condition;

FIG. 6 is an enlarged top plan view thereof.
